UNITED STATES PATENT OFFICE.

NATHANIEL H. MCLEAN, OF THE UNITED STATES ARMY.

WINDOW-CURTAIN FIXTURE.

Specification of Letters Patent No. 30,236, dated October 2, 1860.

To all whom it may concern:

Be it known that I, NATHANIEL HENRY MCLEAN, lieutenant U. S. Army, have invented a new and Improved Window Curtain or Shade Fixture for Raising and Lowering the Curtain or Shade and Holding the Same at any Height Desired; and I do hereby declare that the following is a full, clear, and exact description of its construction and 10 operation, reference being had to the annexed drawing, making a part of this specification and representing a cross-section.

The fixture consists of a case A B C D, in which works a large wheel or roller 1, two 15 small wheels or rollers 2 and 3, a sliding carriage E F G H, a spring S, and a rod R, which component parts are arranged and work as follows:—The large wheel or roller 1 turns with its axis, which axis turns in 20 holes in the face and back of the case A B C D, projecting to the front where it is finished with a square shoulder O, made to fit a socket in the end of the roller to which the curtain or shade is attached. This 25 large wheel or roller has no other motion than turning with its axis. Immediately above the large wheel or roller 1 are two small wheels or rollers 2 and 3, which turn on axes passing through the ends of the carriage E F G H, the rollers just clearing the 30 bottom of the carriage and extending below the ends of the carriage, so as to press against the large wheel or roller 1. These small wheels or rollers have also a movement 35 with the carriage E F G H, which moves up and down in the case A B C D, in which it is fitted so as to just play smoothly.

To the center of the top of the carriage E F G H is fastened a rod R, which passes 40 up through a hole in the top of the case

A B C D and directs the movement of the carriage. Around the rod R and confined between the tops of the case A B C D and carriage E F G H is a spring S, which pressing the carriage down maintains the 45 friction between the wheels or rollers 1, 2, 3 and an endless cord or tape T, which passes over 1 and under 2 and 3, which cord or tape is directed by passing between the face and back of the case A B C D. 50

When the cord or tape T is drawn to raise or lower the curtain or shade, the wheels or rollers rotate, and as number 1 turns with its axis the square shoulder O on the end of the axis turns the roller to which the 55 curtain or shade is attached. To any reasonable inequality in the endless cord or tape T the carriage holding the small wheels or rollers will yield, moving upward, being directed as stated by the rod R, and under 60 the pressure of the spring S. The friction is thus preserved regardless of the loss of thickness from wearing or stretching of the endless cord or tape T. When the endless cord or tape T is not drawn the pressure 65 exerted by the spring S will hold the wheels or rollers stationary and retain the curtain or shade at any height.

What I claim as my invention, and desire to secure by Letters Patent, is— 70

The large wheel or roller (1) and the two wheels or rollers above it (2 and 3) the sliding carriage E F G H, the spring (S) and rod (R) when arranged and combined substantially as and for the purpose specified. 75

NATHANIEL HENRY MCLEAN.
